MOUTHPIECE FOR WOODWIND INSTRUMENTS

Harry Chance, Birmingham, England

Application April 23, 1948, Serial No. 22,739
In Great Britain May 20, 1947

3 Claims. (Cl. 84—383)

1

This invention relates to wind-operated musical instruments, such for instance as saxophones or clarinets, the object of the invention being to provide an improved mouthpiece.

According to the present invention I provide a mouthpiece for a wind-operated musical instrument comprising a tubular part at one end for engagement with the instrument, a body part having a flat or other surface extending along one side from the tubular part to the opposite end, this surface being adapted to receive a reed, the inlet end of the mouthpiece being of wedge shape, formed on one side by the said surface and on the opposite side by a surface which is inclined thereto, the opening through the tubular part being extended rearwardly through the body of the mouthpiece and terminating in an elongated slot in the flat or other surface beneath the reed so that the wedge-shaped portion forms a channel, and this channel being provided with a restriction situated in advance of the inlet end.

Preferably the restriction is situated about midway between the inlet end of the mouthpiece and the opposite end of the slot in the flat or other surface, and it may be formed by thickening the lower wall of the wedge-shaped portion locally.

The upper surface of the thickened portion may be of V shape, or approximately so, and the line formed by the angle of the V may be slightly inclined upwardly and forwardly, or approximately parallel to the axis of the tubular part.

The invention is illustrated in the accompanying drawings, wherein:

Figure 1 is a view in side elevation;

Figure 2 is a plan view;

Figure 3 is a longitudinal section on the line 3—3 of Figure 2;

Figure 4 is a perspective view;

Figure 5 is a section on the line 5—5 of Figure 3;

Figure 6 is a section on the line 6—6 of Figure 3; and

Figure 7 is a section on the line 7—7 of Figure 3.

In the construction illustrated the mouthpiece is made of moulded material, or it may be made of metal, and it is provided with a tubular portion 10 adapted to push into or onto the end of the instrument. The mouthpiece further comprises a body portion 11 on the upper side of which is a flat surface 12, or a surface which is flat for the major part of its length.

The entrance portion 13 of the mouthpiece is of wedge shape, the upper side 14 being formed

2

by a continuation of the flat 12 but curved downwardly, and the opposite side being formed by a surface 15 which is inclined sharply to the part 14. The exterior surface of the part 15 is curved in section, as shown at 16 in Figure 5.

The opening 17 in the tubular part 10 is extended rearwardly and is then directed upwardly so that it terminates in an elongated slot 18 in the surfaces 12 and 14.

10 A restriction is provided in the lower wall of this inlet portion, the restriction being formed by a local thickening of the material, as shown at 19, the upper surface of the thickened portion being of approximately V shape, as shown at 20, 15 and the angle 21 of the V being either inclined upwardly in a forward direction, or approximately parallel to the axis of the tubular part 17.

15 The effect of providing the restriction near the entrance end of the mouthpiece is to improve the 20 playing qualities of the instrument by modulating the overtones so that they do not clash with the fundamental note being played. The modulation of the overtones or higher harmonics of the fundamental note by which they are 25 pitched slightly sharper than hitherto is caused by the form of the restriction.

A reed 22 is secured to the surface 12 and extends over the slot 18.

What I claim then is:

30 1. In a mouthpiece for a wind-operated musical instrument having an inclined wall near the forward end thereof, side walls and an opening opposite said inclined wall over which the reed is placed, an inwardly directed projection of V shape cross section formed integrally with the inclined wall of the mouthpiece, the side walls of said projection diverging towards the opening opposite the inclined wall of the mouthpiece.

40 2. In a mouthpiece for a wind-operated musical instrument having an inclined wall near the forward end thereof, side walls and an opening opposite said inclined wall over which the reed is placed, an inwardly directed projection of V shape cross section formed integrally with the inclined wall of the mouthpiece, said projection being disposed longitudinally of the mouthpiece, the line formed by the angle of the V being inclined towards the forward end of the mouthpiece and towards the opening formed therein

45 opposite the inclined wall, and the side walls of said projection diverging toward the opening opposite the inclined wall of the mouthpiece.

50 3. In a mouthpiece for a wind-operated musical instrument having an inclined wall near the forward end thereof, side walls and an opening op-

55 55

posite said inclined wall over which the reed is placed, and inwardly directed projection of V shape cross section formed integrally with the inclined wall of the mouthpiece, said projection being disposed longitudinally of the mouthpiece and midway of the ends of the opening of the mouthpiece, the line formed by the angle of the V being inclined towards the forward end of the mouthpiece and towards the opening formed therein and the side walls of said projection diverging toward the opening opposite the inclined wall of the mouthpiece. 10

HARRY CHANCE.
